Inventor

James S. Spainhour,
By his attorney

Dr. Anthony Urena

UNITED STATES PATENT OFFICE.

JAMES S. SPAINHOUR, OF HEMPSTEAD, NEW YORK, ASSIGNOR OF ONE-HALF TO SIDNEY E. BECKWITH, OF HEMPSTEAD, NEW YORK.

AEROPLANE.

1,270,339.

Specification of Letters Patent. Patented June 25, 1918.

Application filed June 9, 1917. Serial No. 173,681.

To all whom it may concern:

Be it known that I, JAMES S. SPAINHOUR, a citizen of the United States, residing in Hempstead, Long Island, New York, have 5 invented certain new and useful Improvements in Aeroplanes, of which the following is a specification.

My invention relates to rudders and elevators which are mounted on the rear end 10 of the body or "fuselage" of an aeroplane. Aeroplanes often carry spare parts such as a rudder of one design and one or more elevators of another design. One important 15 feature of my invention is to make the rudder and the two elevators absolutely identical in shape and size, and also to make them interchangeable, thereby making it possible to reduce the number of spare parts which need to be carried. My invention 20 also provides for the substitution of one of these parts for another.

It is a common expedient to extend the pivot line to a position where each of the 25 vanes, rudder and also the elevators has one part lying in front of the pivot and another part in the rear. In other instances the vane lies entirely in the rear of the pivotal line. My present invention is applicable to either type of vane.

30 The accompanying drawings illustrate an embodiment of the invention.

Figure 1 is a rear end view in elevation.

Fig. 2 is a plan of the same,

Fig. 3 is a side elevation.

35 Fig. 4 is a longitudinal section on the line 4—4 of Fig. 5.

Fig. 5 is a view, in elevation, of the hinge attached to the fuselage.

Referring to Fig. 1 the rudder A and the 40 elevators B, which are identical in shape and size, are shown each in its middle position, these parts being mounted on the rear end of the fuselage, which is T-shaped, and having a horizontal portion C and a vertical 45 portion D. The elevators are simply rudders pivoted on a transverse horizontal line of the back of the machine while the rudder proper is a vane pivoted on a transverse vertical line at the back of the machine. That is, the rudder A is pivoted along the edge D, Fig. 3, and the elevators B are pivoted along the edges E, E, Fig. 2.

The arc in which the vanes swing is indicated by dotted arrows. Referring to 55 Fig. 2, the inner edges F of the elevators

begin at a point close to the pivot or hinge of the rudder A, and extend obliquely outward so as to allow room for the swinging of the rudder to the right or to the left, the plane of the elevators intersecting that of the rudder (see Fig. 3) so that they would interfere with the swinging of the latter except for the flaring of the edges F. The lower edge G (Fig. 3) of the rudder is similarly inclined upward, the inner vertical pivoted edge extending practically the full length of the vertical limb D of the rear end of the fuselage. This feature of making the rudder and elevators absolutely identical in shape and size is an important one. 70 By making these elements identical, I make them also interchangeable (even the hinge parts being identical) and thereby reducing the number of spare parts which need to be carried. 75

It is also possible to substitute one of these parts for another. For example, in case one elevator is broken and no spare parts are at hand, the rudder may be substituted for the broken elevator and the 80 flyer can get along without a rudder.

The rudder A and elevators B are each connected separately to the T-shaped end of the machine by means of a hinge which is of a peculiar design to give a long bearing. 85 The hinge comprises a hollow hinge pin H (Fig. 4), usually of steel bolted or otherwise fastened to a strut O which forms a part of the canvas covered frame of the vane (rudder or elevator), said hinge pin H being surrounded by a tube J of brass which in turn is embraced by a loop K, the leaves L of which are fastened to the rear member of the fuselage, and a loop M, the leaves N of which are fastened to the strut O of the 90 rudder or elevator. 95

Though I have described with great particularity in detail a certain specific embodiment of my invention, yet it is not to be understood therefrom that the invention is 100 restricted to the specific embodiment disclosed. Various other modifications in detail and in the arrangement of the parts may be made by those skilled in the art without departure from the invention as defined in 105 the following claims.

What I claim is:—

1. An aeroplane having mounted on its rear end a rudder and a plurality of elevators, said rudder and said elevators being 110

identical in shape and size, the plane of the elevators intersecting the rudder and the inner edges of the elevators flaring outward to permit the rudder to swing freely between them.

2. An aeroplane having mounted on its rear end a rudder and a plurality of elevators, said rudder and said elevators being identical in shape and size, and being interchangeable.

3. An aeroplane having mounted on its rear end a rudder and a plurality of elevators, said rudder and said elevators being interchangeable.

15 4. An aeroplane having a rudder and elevators, and hinges connecting the said rudder and elevators to the rear end of the

aeroplane, the portions of said hinges on the rudder being adapted for operative engagement with the portions of the elevator hinges on the end of the aeroplane, and vice versa, so as to permit the interchange of the rudder with the elevators.

5. An aeroplane having a vane hinged thereto, the hinge comprising a pin fastened to a part of the frame of said vane, a tube surrounding said pin and loops surrounding said tube and fastened one loop to the frame of the vane and the other to the frame of the aeroplane.

In witness whereof I have hereunto signed my name.

JAMES S. SPAINHOUR.
